SINGEING APPARATUS AND METHOD

Richard R. Cone, Gastonia, N. C., assignor to
 Threads, Incorporated, Gastonia, N. C., a corporation of North Carolina

Application July 1, 1946, Serial No. 680,599

12 Claims. (Cl. 28—63)

1

This invention relates to a singeing apparatus for singeing yarn, cloth, and the like and is especially adapted for the singeing of yarn, in that, the singeing flame is adapted to penetrate between the yarn and singe all portions thereof.

The invention comprises a conventional creel having drop wires through which the ends of yarn are passed and said ends are passed through a suitable reed and across a set of burners, and then it is carried onto another set of burners spaced some distance away from the first set of burners, after which it passes over a roller and is reversely directed beneath the last burner unit and is wound onto a suitable warp beam in the form of a chain warp. Means are also provided for automatically stopping the entire apparatus when an end in the yarn breaks and upon stoppage of the machine, the supply of fuel, such as gas, is automatically cut off to the two burner units and compressed fluid is blown across the burners to automatically extinguish any flame, which may remain due to the deposit of lint and the like, or residual gas.

It is an object of this invention to provide a singeing apparatus having two spaced sets of singeing burners across which the warp is directed together with means for automatically stopping the machine, when an end breaks or when the forward speed of the warp is not sufficient to prevent its being burned by the burners across which it is directed, together with means for automatically stopping the flow of fuel to the burners upon stoppage of the warp together with means for blowing compressed air across the burners to extinguish any remaining flame, which might be present on the burners, and thus to prevent burning of any of the warp ends.

It is another object of this invention to provide in a singeing machine a pair of singeing devices disposed in spaced relation to each other, and in which means are provided for automatically extinguishing the flames in the singeing apparatus, when the forward speed of the warp threads across the singeing devices falls below a predetermined rate of speed, together with means for automatically igniting both of the singeing devices upon starting of the singeing operation and having means for automatically cutting off the fuel to the second singeing device after it has run a predetermined time so as to singe that portion of the warp disposed between the two singeing devices which has not been properly singed by the first singeing device upon stoppage of the machine.

Some of the objects of the invention having

2

been stated, other objects will appear as the description proceeds when taken in connection with the accompanying drawings, in which:

Figure 1A is a plan view of the second or rearmost singeing apparatus;

Figure 1B is a plan view of the forward or first singeing apparatus through which the yarn passes before it reaches the second singeing apparatus;

10 Figure 2A is a side elevation of Figure 1A, looking from the lower side of Figure 1A, and showing schematic wiring in association therewith;

15 Figure 2B is a side elevation of the structure shown in Figure 1B, and looking from the lower side of Figure 1B and showing some of the wires in schematic form;

Figure 3 is a side elevation looking at the other side of Figure 2B;

20 Figure 4 is a vertical sectional view on an enlarged scale of one of the creel drop wire units, shown in elevation immediately to the right of Figure 4 in Figure 3;

Figure 5 is a cross sectional view taken along 25 the line 5—5 in Figure 1A;

Figure 6 is an elevation looking from along the line 6—6 in Figure 1A, with central portions of the apparatus being broken away;

Figure 7 is a schematic wiring diagram associated with the rearmost burner and associated parts;

Figure 8 is a schematic wiring diagram of a portion of the creel and the warper mechanism.

Referring more specifically to Figures 3 and 4 35 of the drawings, the numeral 10 indicates the front portion of a conventional creel having a plurality of drop wire mechanisms located therein, there being a drop wire mechanism for each of the strands coming from the creel. The strands 40 are indicated at 11. The front portion of the creel 10 comprises a plurality of vertically disposed posts 12, having a plurality of insulating blocks, such as wooden blocks 13, secured transversely thereacross by any suitable means, such as bolts 14. The bolts 14 penetrate suitable angle brackets 15, which are secured to a transverse angle iron 16 by any suitable means, such as a bolt 17.

Supported by blocks 13 is a transverse metallic 50 bar 18, in which a plurality of eyelets 19 are mounted, said eyelets being preferably of porcelain or some other insulating material, and there being an eyelet for each of the strands of yarn 11. There is also another insulating block, such as a wooden block 20, associated with each block

13 and between blocks 20 and 13 is mounted a strap member 21, which extends downwardly, and these strap members 21, have secured thereto as by means of a bolt 22, a metallic bar 23. There is also mounted in block 20 a transverse rod 24 over which the strands of yarn 11 pass. Mounted for up and down movement on the metallic bar 23 is a drop wire 26, which has its upper end in the form of a circle and clampingly holding an insulating eyelet 27 therein and through which a strand of yarn 11 passes.

It is thus seen that the fixed eyelets 19 and the transverse rod 24 support the strands of yarn 11 and thus hold the eyelet 27 in elevated position as long as the strand is not parted. The wire 26 extends downwardly and it encircles the metallic bar 23, and has a horizontally projecting tail 28, which is adapted to fall onto a metallic rod 29, when a strand of yarn 11 supporting a drop wire 26 and an eyelet 27 parts and allows the horizontal portion 28 to engage both the bar 23 and the metallic rod 29.

Secured to the bolt 22, which is electrically connected to bar 23, is a wire 30, all of these wires 30 being joined to a common wire 31, which is connected to one side of solenoid coil 32, having a solenoid core 33. To the other side of the solenoid coil 32 is connected a wire 34.

Wire 34 is connected to one side of a coil 35 of a reducing transformer 36. From the other side of coil 35, a common wire 37 is led to a lead 40 for each horizontal row of eyelets 27, and this wire 40 is connected to the metallic bar 29. The transformer 36 has another coil 41, which is connected to a suitable source of power by wires 38 and 39a having therein a switch 42 for cutting on and off the power to the transformer 36.

A conventional warper is indicated at 45, and this is a conventional design having a bar 46 over which the strands 11 are passed through a reed 47, where they are formed into a sheet to be passed across the two singeing units. The warper is also equipped with a reed 43 through which the sheet of warp passes. This warper is of conventional design and only portions thereof will be described. The warper is driven from an overhead pulley 48 driven by a suitable source of power, and on which is mounted a belt 49, which engages either a tight pulley 44 or a loose pulley 50 mounted on a shaft 51. This shaft 51 has a pinion 52 thereon, which meshes with a pinion 53 mounted on a shaft 54, which projects through the machine.

On shaft 54 is disposed an elliptical cam 56, which is adapted to oscillate a lever 57, pivoted for oscillation, as at 58. To the free end of this lever 58 is pivotally secured a link 60, and oscillation of lever 57 will cause up and down movement of link 60. Link 60 passes through a guide 61 secured on the side of the machine, and has a shoulder 62 on one side thereof. Its upper end is adapted to engage a projection 63 disposed on a link 64, which is pivoted to the free end of a lever 65 mounted on an oscillatable shaft 66, which ordinarily is employed in the stop motion mechanism, but in the present instance, this stop motion mechanism is eliminated, as it is unnecessary.

The right hand end of the solenoid core in Figure 3 is pivotally secured to the lower end of link 64. Pivoted for oscillation, as at 67, is a foot lever 68, having secured thereto and intermediate its end, as at 69, a sliding link 70. This link projects upwardly and has its upper end shoul-

dered, as at 71, and is supported by a guide 72 secured on the side of the warper frame. Pivotally mounted on the side of the warper frame, as at 73, is a bell crank lever 74 having a forwardly projecting portion 75, which projects forwardly and towards the observer in Figure 3 alongside the left hand edge of the upper end of link 70.

When a drop wire falls in one of the drop wire switches previously described and shown in detail in Figure 4, the solenoid coil 32 will be energized to move the solenoid core 33 to the left in Figure 3. This will cause the shoulder 62 on its downward movement to engage the right hand end of bell crank 74, which will pivot its upper end to the right or pivot the bell crank 74 in a clockwise manner in Figure 3, which will move the link 70 in a clockwise manner in Figure 3 and cause its shoulder to be removed from beneath the left hand side of the looped guide 72, and since shaft 67 has a plurality of weighted levers thereon, not shown, this will cause the foot lever 68 to move in a counter-clockwise direction in Figure 3 to raise link 70 and this will allow oscillation of shaft 67 in a counter-clockwise manner in Figure 3, and shaft 67 has conventional belt shifting means thereon, not shown, which will shift the belt 49 to the loose pulley 50 on shaft 51 and stop the machine.

Shaft 54 has also secured thereon a sprocket wheel or pulley 80 on which is mounted a sprocket chain or pulley belt 81, which projects forwardly to a point between the two singeing devices and is mounted on a sprocket wheel or pulley 82 secured on one of the rollers 83 of a ball warp roll holder. This warp roll holder has end portions 84 and 85 in which there is also mounted another roll 86 and one of the housings 84 or 85 has conventional gearing mechanism therein, not shown, which connect rollers 83 and 86 together so as to cause their top surfaces to run in the same direction and on which is adapted to rest a warp beam 87, onto which the ball of warp is adapted to be wound. Also the housings 84 and 85 have mounted therein a reverse screw cam shaft 88 and suitably driven by the gearing in one of the housings 84 or 85 and on which is mounted for back and forth travel a guide member 89, having an eye 90 therein through which the warp in rope form is adapted to be guided onto the warp beam 87.

The two singeing devices will be referred to as the first singeing device, and the second singeing device. These two singeing devices are identical in structure, except that they are reversed as to position, that is, the second singeing apparatus is identical to the first singeing apparatus, except that its position is turned 180°, and therefore, a description of one will refer to the other with the prime notation added to the parts of the second singeing apparatus.

The singeing apparatus is supported by four vertically disposed pipes 91, which are secured to the floor of the building by a suitable flanged pipe fitting 92, which are suitably secured to the floor by screws and is of conventional design. The upper ends of these pipes 91 have substantially semi-circular cuff members mounted thereon for supporting the horizontal side portions of the singeing apparatus.

The singeing apparatus comprises a plurality of transversely disposed spaced pipes 93, 94, 95 and 96, the pipes 93, 94 and 95 having secured on the ends thereof suitable T's 97, 98, 99, which are joined together by nipples 100. The T's 99

have secured thereto nipples 101, which have elbows 102 on their other ends and between the elbows 102, the pipe 96 is disposed.

Secured to the T's 97 are nipples 103 to which one end of a tube 104 is connected, said tube being usually referred to under the trade-mark "Venturi," the other end of the venturi 104 being connected to a suitable air mixing valve 105. Monuted in the ends of the portion 105 are suitable rotatable air inlets 106, the venturi and the air inlets being conventional.

Secured to the portions 105 of the venturi 104 and projecting downwardly are nipples 107, which have elbows 108 therein, and connected to elbows 108 are nipples 109, which are connected to a solenoid valve 110 normally held in open position during operation of the entire apparatus, and upon de-energization of the machine, the valve 110 moves to closed position, from which suitable wires, to be presently described, are led. Connected to the other side of the solenoid valves 110 is a nipple 111, which is connected to a T 112 and T 112 is connected by a pipe 113 to a T 114.

Connected to the T's 112 are nipples 115 to which a manually operable valve 116 is connected which has a pipe 117 leading therefrom and which is led beneath each end of the pipes 93 to 96 inclusive. Each of the pipes 117 have T's 118 therein to which are connected pilot light pipes 120, which are directed upwardly and then over to where their open ends are in close proximity to a perforated conventional ribbon 121 disposed in each of the pipes 93 to 96 inclusive and through which the gas escapes, there being a small quantity of gas passing through pipes 120 at all times to maintain a pilot light at each end of the perforated ribbons 121.

Gas is supplied, not only to the pipes 93 to 96 inclusive, but also to all of the pilot pipes 120 by means of a pipe 122 connected to a suitable source of gas, and being directed underneath the singeing apparatus and connected to T 114. This pipe 122 has a manually operable valve 123 therein, by means of which the gas can be cut off from the burners when the machine is not in operation, such as closing down at the end of a shift, or at the end of the day.

In the case of stoppage of the travel of the warp as by the breaking of an end, resulting in the closing of one of the switches in the creel board, it is absolutely necessary that the gas be cut off immediately and the solenoid valves 110 accomplish this, as will be presently described, but it often happens that lint has fallen down onto the pipes 93 to 96 inclusive adjacent the perforated ribbons 121 and will continue to burn after the warp is stopped, thus resulting in the burning of several ends of the warps, which requires quite a bit of time in passing these burnt ends on through the apparatus, and securing them to the winding apparatus.

In order to insure that no flame of any kind will remain upon stoppage of the travel of the warp, there has been provided means for supplying a compressed fluid, such as a suitable extinguishing fluid, such as carbon dioxide, or ordinary compressed air for causing blasts of this compressed fluid to sweep across the upper parts of the pipes 93 to 96 inclusive, and of course, across the perforated ribbons 121 to blow any flames therefrom. With this purpose in view, there has been provided adjacent the pipes 93 to 96 inclusive pipes 125, 126, 127 and 128, which in the present form are shown as rectangular in cross section, and each of these pipes has a

slot 129 extending longitudinally thereof so that a sheet of compressed fluid is emitted from these slots 129 to sweep across the upper portions of the pipes 93 to 96 inclusive and the perforated ribbons 121 mounted therein. It is, of course, evident that these pipes could be of any other desired shape so long as the axis of the stream of compressed fluid is directed across the tops of the pipes 93 to 96 inclusive.

The pipes 125 to 128 inclusive are supported by means of a plurality of vertically disposed pipes 130, which at their lower ends are joined to a horizontal pipe 131 made up collectively of nipples and elbows, and which pipe 131 has connected thereto a supply pipe 132, which has a solenoid valve 133 therein, normally closed, having wires 175 and 176 leading therefrom, which will presently be described. From the other side of solenoid valve 133 normally held in closed position, a pipe or hose 134 is led to a suitable source of compressed fluid 124.

After the yarn has passed over the two singeing devices, it is passed through the suitable reed 136 of a conventional lease-taking apparatus. This reed 136 is mounted in side stands 137 and 138 disposed on each side of the machine and conventional means are employed for first raising the sheet of warp to pass a lease-stick therethrough and then the reed 136 can be lowered below the ordinary level of the sheet of warp to pass another lease-stick therethrough to insert a lease thread. These stands 137 and 138 are joined together by a suitable supporting rod 139.

After the warp threads 11 pass through the reed 136, they are brought through a substantially U-shaped member 140 crimped inwardly at its upper end to form a kind of eye, which converts the sheet of warp into a compacted set of warp threads, which are passed over a roller 141 mounted in a stand 142 and on which is mounted a support 143, which supports the constricting member 140.

The roller 141 is contacted by a conventional centrifugal sling switch 144. The warp ends 11, after being converted into condensed form, are hereinafter referred to by reference character 145, and are directed forwardly underneath the second singeing apparatus and directed through eye 90 and secured around the beam 87, and is wound therearound in a conventional manner well known as ball warping.

The centrifugal switch indicated schematically at 144 is mounted on a suitable member 146 pivoted as at 147 on support 143 and has a roller 148 which drives a centrifugal mechanism, which is conventional and which is associated with switch 144 to hold the switch open while the roller 141 is running at regular speed, but when the machine stops or should slow down, then this centrifugal switch 144 will become closed and operate the solenoid valves for closing the gas line supplying gas to the burners and at the same time opens the compressed fluid valves for admitting compressed fluid to the rear burners for a predetermined time to extinguish any blaze that might be on these burners. This centrifugal switch is disclosed in Patent No. 1,493,846. The shaft 23 in said patent represents the shaft on which roller 148 is fixed in this application. The roller 148 contacts and is driven by the pulley 141.

The control system for the two singeing units is mounted on a panel 149 and derives its power from any suitable source of power such as two

main power lines 150 and 151 connected to a suitable source of 110 volt A. C. current. Wire 150 leads to one side of the centrifugal switch 144. Connected to wire 150 is a wire 152 which leads into a suitable vacuum tube time delay relay indicated at 153. Any suitable time delay relay could be used, but in the present hookup I employ a General Electric type such as shown in Patent No. 2,171,347 having General Electric Catalogue Handbook section CR7504-A3. This is also listed in a descriptive folder No. G. E.—A2902. Connected to wire 152 is a wire 154 which goes to contact 155 on a double throw, double pole relay 162. Wire 151 leads from a source of electrical energy to one side of solenoid air valve 133. From the other side of solenoid 133 a wire 156 is led to a conventional clock motor delay switch 157, where it is connected to contact 158, the structure of which is fully shown and described in patents numbered 1,977,184; 1,977,185; 1,977,186; 1,935,208; 1,996,375; 2,353,305; and 2,049,261. From post 159 of clock motor delay switch 157, a wire 160 leads to post 161 on the double throw, double pole relay switch disposed in housing 162, the structure of which is shown in Patent No. 2,259,127. Connected to wire 160 is a wire 163, which is connected to contact post 164 on delay switch 157. Switch 157 has a knock-off switch and a micro switch as a part thereof. From post 165 on delay switch 157 a wire 166 is connected to one side of solenoid valve 110' and controls the flow of gas to the second singeing assembly. From the other side of solenoid valve 110' a wire 167 leads to a contact post 168 on the double throw, double pole relay switch housing 169. From contact post 170 of double throw, double pole relay 169 a wire 171 leads to contact post 172 in clock motor delay switch disposed in housing 173. The switch in housing 169 is shown in Patent No. 2,259,127. The switch in housing 173 is shown in patents numbered 1,977,184; 1,977,185; 1,977,186; 1,935,208; 1,996,375; 2,353,305 and 2,049,261. The structure of switch 173 is the same as switch 157. From contact 174 on switch housing 173 a wire 175 leads to one side of solenoid air valve 133'. From the other side of solenoid air valve 133' a wire 176 leads to and is connected to wire 166. Also connected to wire 166 is a wire 177, which leads to contact post 178 on clock motor delay switch housing 173. This housing also has a contact post 179 to which a wire 180 is connected, said wire 180 being connected to wire 171. Connected to post 182 leading into housing 169 of the double throw, double pole relay is a wire 183 which is connected to a post 184 of housing 153. Housing 169 also has a post 185 to which a wire 186 is connected, and which wire 186 is connected to wire 166. The housing 153 also has a post 187 to which a wire 188 is connected, said wire 188 also connected to post 189 on housing 162. Also connected to wire 188 is a wire 190 which is connected to one side of the coil or solenoid gas controlled valve 110.

The other side of solenoid gas controlled valve 110 has connected thereto a wire 191, which is also connected to wire 151 as at 192. Connected to wire 151 is a wire 193 which is connected to wire 166 as at 194 and also connected at 194 is a wire 195, which leads to a post 196 on switch housing 153. Wire 193 has connected thereto a wire 197 which in turn is connected to a post 198 on relay housing 162. This housing 162 also has a post 199 to which a wire 200 is connected, which wire 200 is connected to the other side of

centrifugal switch 144. Double throw, double pole, relay mechanism disposed in housing 162 has a post 201 to which a wire 202 is connected and which wire is also connected to a post 206, on time delay relay housing 153. Switch housing 162 has also a post 204 to which a wire 205 is connected which leads to a post 203 on time delay relay housing 153.

Wire 152 which is connected to wire 150 and also connected to a post 207 on time delay relay housing 153, is also connected by wire 208 to post 209 in housing 169.

Method of operation

With a strand 11 leading from each package in the creel through the drop wire eyelet 21, and with the parts in position, as shown in the drawings, and especially referring to Figure 3, the lever 57 will oscillate along on its pivot 58 and thus links 60 and 64 will be moved up and down as a unit until an end 11 parts, which will cause one of the drop wires 26 to drop, which will close the circuit to energize solenoid coil 32, which will swing the lower end of lever 64 to the left in Figure 3, which will push the upper end of lever 60 to the left in Figure 3 and cause its shoulder 62 to engage the horizontally projecting end of bell crank 64 and whose upper end 71 will swing link 70 on its pivot 69 to allow the weight not shown on shaft 67 to move lever 68 and link 70 upwardly and this will allow the shaft 67 to swing in a counter-clockwise manner, which will shift the belt 49 from the tight pulley 44 to the loose pulley 50 and stop the machine. As the machine does not stop instantly, since there is some inertia in the moving parts, the roller 148 will slow down and thus cause centrifugal switch 144 to close. This will cause current to flow from wire 150 through switch 144.

When that switch is closed the current goes on line 200 up to post 199 on relay 162 furnishing the current to one side of the coil in that relay. From post 199 the current goes through the coil to 198, back up to line 197 to 193 to 151 and to the other side of the A. C. current. The hot side of the A. C. current comes off from line 150 to line 152, line 154 up to post 155 which is the center terminal on the double throw relay 162. When the coil in the relay 162 is energized, the current will pass through post 155 to post 189 into line 190 up to solenoid valve 110 along line 191, 192, it is connected directly to line 151 which is the opposite side of the A. C. line or the ground side. When post 189 receives the current, it also passes along line 188 to post 187 and through the normally closed micro-switch in the vacuum tube time relay to post 184 and along line 183 to post 182 in the number 2 double pole, double throw relay, box 169. Passing through a conventional coil in relay 169 to post 185 it goes out along line 186, post 194, along line 193 to line 151, the ground side of the A. C. supply. Now, starting at the hot side of the A. C. supply, passing along line 150 through line 152, through line 208 to post 209, the center terminal on relay 169. When that relay is energized, the current passes through post 168 out along line 167 to valve 110' and then out along line 166 to post 194 through line 193 back to line 151, the ground side of the A. C. supply. Now, through having the centrifugal sling switch close mechanically, we have energized both relays 162 and 169 which shut off the current supply to valves 110 and 110', turning off the gas on the #1 and #2 sets of burners.

When the relay 162 is de-energized by opening of switch 144, the current from the hot side of the A. C. supply line flowing to center terminal 155 will pass through the normally closed contacts to 161 along line 160 to terminal 159 of a micro-switch portion of clock motor delay 157 and through its normally closed circuit to post 158 along line 156 to air-valve 133 and then back out along ground wire 151 which is the other side of the A. C. supply. At the same time, when relay 162 is de-energized and current is flowing through post 161, it also flows along line 163 to post 164 of the clock motor, 157, energizing the clock motor and passing through 165 to line 166 to post 194 along line 193 to the opposite side of the A. C. supply, line 151.

When the clock motor is energized it begins a slow rotation of a knock-off shaft, which after a predetermined delay, opens the normally closed contacts 159 and 158 thus opening the circuits to air-valve 133 and closing the air supply through that valve. In like manner as described for relay 162, when relay 169 is deenergized, the current passes through post 209 to post 170, in a normally closed position, to line 171 to line 180 to post 179 in clock motor 173. Energizing this motor it passes post 178 to line 177 to line 166 to post 194 to line 193 and to line 151 which is the opposite side of the A. C. supply. At the same time, when coming off of post 179 through line 171, it passes on to post 172, which is one side of a normally closed micro-switch. Passing on to the other side post 174 and down through line 175 it goes to #2 solenoid air-valve, 113'. Energizing this valve, it passes on out through line 176 to 166 to post 194 through line 193 to line 151, which is the opposite side of the A. C. supply. Thus we have both solenoid air-valves opened, when the relays 162 and 169 are de-energized. The clock motor 173 operates in the same manner as 157. When it has been energized, a knock-off shaft turns around and after a predetermined delay opens the normally closed contacts 172 and 174, thus shutting off the air supply through valve 133'. Now with the centrifugal sling switch closed by virtue of the rate of travel of the yarn over tailstock being above a predetermined number of feet per second, both relays 162 and 169 are energized opening up both gas valves, 110 and 110', which enables both the first and second singeing devices to be ignited by the pilot lights. After a short predetermined delay, the entire second burner assembly must become inoperative and the flame be blown out, for the second assembly is used only to singe that portion of yarn that the first set has skipped when coasting to a stop. This is accomplished through the vacuum tube time delay relay, #153. This relay has a complete circuit coming through the hot side of the A. C. supply along line 150, line 152 to post 207 and out along post 196, along line 195 to post 194 along line 193 to line 151, the opposite side of the A. C. supply. Post 203 is connected to post 196 and goes to post 204 along line 205. When relay 162 is energized, the current flows from post 204 to post 201 back along line 202 to post 206. This closing of the circuit from post 196 to post 203 and then post 206 is necessary for the proper operation of the vacuum tube circuit. After a predetermined time delay, in this case adjustable by manual set, the current passing from post 187 to post 184 is interrupted, de-energizing relay 169, thus

shutting off the circuit to gas valve 110' and starting or energizing the motor delay switch 173 and opening air valve 133'. As stated before after a short delay, air valve 133' is again closed and the air flow interrupted. This operation leaves the entire #2 burner assembly inoperative until the next yarn stop produces a skipped or ungassed portion in the yarn.

In the drawings and specification, there has been set forth a preferred embodiment of the invention and although specific terms are employed, they are used in a generic and descriptive sense only, and not for purposes of limitation, the scope of the invention being defined in the claims.

15 I claim:

1. In a singeing machine through which a plurality of strands of yarn in sheet form are passed for singeing, comprising two singeing units spaced from each other a substantial distance, means for guiding a sheet of yarn through the first singeing unit and then through the second singeing unit, a roller over which the yarn passes after passing through the second singeing unit and a ball warper having a take-up beam disposed between the singeing units onto which the yarn is wound after passing over said roller, means for stopping the ball warper take-up beam when a strand parts, a centrifugal switch in contact with the roller and means operable by the centrifugal switch when the revolutions per minute of the roller decrease to a predetermined point for rendering inactive the two singeing units.

2. In a singeing apparatus for withdrawing a plurality of strands from a creel and passing the strands through a warper, a pair of singeing devices spaced apart from each other, and each of the singeing devices having a plurality of perforated pipes, means for supplying a gas to the perforated pipes, a solenoid valve in each of the supply means to the perforated pipes, a roller disposed beyond the second singeing device over which the threads are passed after they pass through the singeing devices, a centrifugal switch in contact with said roller, a ball warper having a take-up beam disposed between the two singeing devices, means connecting the warper to the take-up beam for driving the same, the centrifugal switch being adapted to be closed when the revolutions per minute of the roller decrease to a predetermined point, and a circuit leading from said centrifugal switch to the solenoid valves for cutting off the supply of gas to the perforated pipes, means operable by a centrifugal switch upon travel of the threads through the two singeing devices for opening the solenoid valves to supply gas to both of the singeing devices and means operable at a predetermined time after gas has been admitted to the second singeing device for cutting off the supply of gas to the second singeing device after the second singeing device has singed the portion of the thread between the two singeing devices which may not have been singed upon stoppage of the apparatus.

3. In a singeing machine, a pair of singeing units disposed in spaced relation to each other, means for guiding a sheet of yarn across the two singeing units, means for rendering operative both singeing units upon the beginning of travel of yarn across the two singeing units, means automatically operable upon cessation of travel of the yarn for rendering both singeing units inoperative, means operable upon the resumption of travel of the yarn across the singeing units for rendering both of the singeing units

operable, and means automatically operable after a predetermined interval of travel of the yarn across the singeing units for automatically rendering inoperable the second singeing unit, and means for blowing out the residual flame on the singeing units when they have been rendered inoperable.

4. In a singeing apparatus, a pair of spaced singeing units across which a sheet of yarn is passed for singeing the same, means automatically operable upon the beginning of travel of the yarn across the singeing units for supplying gas to both of the singeing units, means automatically operable upon the stoppage of the travel of the yarn across the singeing units for cutting off the supply of gas to the burners, means automatically operable upon the beginning of travel of the yarn across the singeing units for supplying gas to both of the singeing units and means automatically operable after a predetermined interval of travel of the yarn over the two singeing units for automatically cutting off the supply of gas to the second singeing unit, and means for blowing out any residual flame after the supply of gas has been cut off from the singeing units.

5. In a singeing apparatus for withdrawing a plurality of strands from a creel and passing the strands through a warper, a pair of singeing devices spaced apart from each other, and each of the singeing devices having a plurality of perforated pipes, means for supplying a gas to the perforated pipes, a solenoid valve in each of the supply means to the perforated pipes, means operable upon travel of the threads through the two singeing devices for opening the solenoid valves to supply gas to both of the singeing devices, a roller over which the threads are passed after they pass through the singeing devices, a centrifugal switch in contact with said roller, a ball warper having a take-up beam disposed between the two singeing devices, means connecting the take-up beam to the ball warper for driving the same, the centrifugal switch being adapted to be closed when the revolutions per minute of the roller decrease to a predetermined point, and a circuit leading from said centrifugal switch to the solenoid valves for cutting off the supply of gas to the perforated pipes, means operable upon travel of the threads through the two singeing devices for opening the solenoid valves to supply gas to both of the singeing devices and means operable after a predetermined time for cutting off the supply of gas to the second singeing device after the second singeing device has singed the portion of the thread between the two singeing devices which may not have been singed upon stoppage of the apparatus, and means for forcing a compressed fluid across the burners in each singeing unit upon cessation of travel of the yarn for extinguishing any flame remaining thereon.

6. In a singeing apparatus comprising two singeing units disposed in spaced relation to each other, means operable upon starting of the travel of the yarn for supplying gas to the singeing units, means automatically operable upon stoppage of the travel of the yarn for cutting off the supply of gas to the two singeing units, means operable upon starting of the travel of the yarn for supplying gas to the singeing units, means operable after a predetermined time of travel of the yarn across the two singeing units for automatically cutting off the supply of gas to the second singeing unit, and means for forcing a compressed fluid across the burners in each

singeing unit upon cessation of travel of the yarn for extinguishing any flame remaining thereon.

7. In a singeing apparatus, a pair of spaced singeing units across which a sheet of yarn is passed for singeing the same, means automatically operable upon the beginning of travel of the yarn across the singeing units for supplying gas to both the singeing units, means automatically operable upon stoppage of the travel of the yarn across the singeing units for cutting off the supply of gas to the burners, means automatically operable upon the beginning of travel of the yarn across the singeing units for supplying gas to both of the singeing units and means automatically operable after a predetermined interval of travel of the yarn over the two singeing units for automatically cutting off the supply of gas to the second singeing unit, and means for forcing a compressed fluid across the burners in each singeing unit upon cessation of travel of the yarn for extinguishing any flame remaining thereon.

8. Singeing apparatus comprising a perforated pipe, means for supplying gas to the interior of the perforated pipe, so that it can be ignited to burn as it emerges to the exterior of the perforated pipe, means for passing a sheet of warp threads across the perforated pipe and through the flame associated with the perforations in the pipe, means for automatically cutting off the supply of gas to the perforated pipe upon stoppage of the travel of the threads, and means also operable upon stoppage of the travel of the threads for forcing a sheet of compressed fluid across the perforated pipe to extinguish any residual flame on the perforated pipe.

9. Apparatus for singeing yarn, cloth, and the like comprising a pair of gas burners spaced apart from each other, means for conducting the material to be singed across the two gas burners, means operable automatically upon slowing down of the speed of the travel of the material being singed for cutting off the supply of gas to the burners, means automatically operable upon the cutting off of the supply of gas to the burners for projecting a sheet of extinguishing fluid across the burners for extinguishing any residual flame thereon, means automatically operable upon the resumption of travel of the warp for automatically supplying gas to both burners, and means automatically operable after a predetermined time for cutting off the supply of gas to the second burner, while maintaining the supply of gas to the first burner.

10. Apparatus for singeing a sheet of material comprising a pair of gas burners disposed in spaced relation to each other and across which the sheet is adapted to be passed for singeing the same, each gas burner having a pilot tube for supplying a pilot light to each burner, means for supplying gas to each burner, a solenoid valve from the gas supply line to each burner, means operable automatically and controlled by the speed of the material being singed for opening the solenoid valves to admit gas to the burners while the material is traveling across the burners, said means being automatically operable to close the solenoid valves upon a decrease of the rate of travel of the material, means for extinguishing the flames on the burners upon a decrease in the speed of travel of the material, means operable automatically to open the solenoid valves to supply gas to the burners when the material resumes its normal speed of travel, and means automatically operable after a predetermined interval after the resumption of

13

travel of the material for cutting off the supply of gas to the second burner.

11. That method of singeing a sheet of material, such as yarn, cloth and the like, which comprises passing the material across two spaced singeing units, rendering operative both singeing units at the beginning of the travel of the material, and rendering inoperative the second singeing unit at a predetermined time after the beginning of the travel of the material, and automatically rendering both singeing units inoperative upon the travel of the material slowing down below a predetermined rate of speed.

12. That method of singeing a sheet of material, such as yarn, cloth and the like, which comprises passing the material across two gas burners, supplying gas to both gas burners at the

14

beginning of the travel of the material and cutting off the gas to the second gas burner at a predetermined time after the beginning of the travel of the material and automatically cutting off the supply of gas to both burners upon the rate of travel of the material slowing down below a predetermined rate of speed.
